UNITED STATES PATENT OFFICE.

EDGAR F. HATHAWAY, OF HORNELLSVILLE, NEW YORK.

DESIGN FOR A FENCE-STRAND.

SPECIFICATION forming part of Design No. 20,512, dated February 10, 1891.

Application filed December 26, 1890. Serial No. 375,891. Term of patent 14 years.

To all whom it may concern:

Be it known that I, EDGAR F. HATHAWAY, a citizen of the United States, residing at Hornellsville, in the county of Steuben and State 5 of New York, have invented and produced a new and original Design for Fence-Strands, of which the following is a specification.

The object of this design is to provide a peculiarly ornamental and distinguished fence-strand; and its leading features consist in a 10 pair of upper and a pair of lower lines spirally wound throughout their length and oblique cruciform lines, which cross each other centrally between the pairs of spiral lines and 15 extend in transverse lines across the latter substantially at right angles to a horizontal plane.

In the accompanying drawing, the figure is 20 an elevation showing a portion of the fence-strand.

In the drawing, the numerals 1 and 2 indicate the upper pair of spirally-wound lines, and 3 and 4 the lower pair of similar lines. The oblique cruciform lines 5 and 6 cross each

other, as at 5^a, centrally between the pairs of 25 spirally-wound lines, and these cruciform lines extend in upper and lower transverse lines 7 and 8 across the pairs of spiral lines substantially at right angles to a horizontal plane. The transverse lines 7 and 8 are rectilinear 30 and are arranged in pairs with those of each pair in vertical alignment, or approximately so, across the upper and lower pairs of spiral lines.

The form and configuration shown present 35 a novel appearance and provide an ornamental fencing-strand which possesses distinguishing characteristics.

What I claim is—

The design for a fencing-strand, substantially as shown and described.

In testimony whereof I have hereunto set my hand and affixed my seal in presence of two subscribing witnesses.

EDGAR F. HATHAWAY. [L. S.]
